United States Patent Office

Des. 186,911
Patented Dec. 22, 1959

186,911

FRAME FOR A MICROSCOPE OR SIMILAR ARTICLE

Robert F. Barnes, West Henrietta, N.Y.

Application January 15, 1959, Serial No. 54,188

Term of patent 14 years

(Cl. D57—1)

FIG. 1

FIG.3

FIG.2

Fig. 1 is a front elevational view of a frame for a microscope, or similar article, showing my new design;

Fig. 2 is a side elevational view of the same; and

Fig. 3 is a top plan view of the same.

I claim:

The ornamental design for a frame for a microscope or similar article, substantially as shown.
